United States Patent

Des. 235,407
Patented June 17, 1975

235,407

RANGE TOP

Jack J. Tyson, Toledo, Ohio, assignor to
Owens-Illinois, Inc., Toledo, Ohio

Filed Mar. 29, 1971, Ser. No. 129,290

Term of patent 14 years

Int. Cl. D7—02

U.S. Cl. D7—121

FIG. 1

FIG. 2

FIG. 3

FIG. 1

FIG. 2

FIG. 3

FIG. 4

FIG. 1 is a front perspective view of a range top showing my new design;

FIG. 2 is a top plan view thereof;

FIG. 3 is an elevation view thereof;

FIG. 4 is a top plan view of a modified form thereof;

FIG. 5 is a top plan view of a further modified form thereof;

FIG. 6 is a top plan view of an additional modified view thereof; and

FIG. 7 is a top plan view of a further modified form thereof.

The sides of the embodiments shown in FIGS. 4-7 are substantially the same as illustrated in FIG. 3.

The broken lines in FIGS. 1-3 are shown for illustrative purposes only.

I claim:

The ornamental design for a range top, substantially as shown and described.
